ADAMANTANES AND TRICYCLO[4.3.1.1^{3,8}]UNDECANES

William W. Prichard, Hockessin, Del., assignor to E. I. du Pont de Nemours and Company, Wilmington, Del., a corporation of Delaware
No Drawing. Filed June 18, 1964, Ser. No. 376,259
10 Claims. (Cl. 260—563)

ABSTRACT OF THE DISCLOSURE

The compounds of the invention are a class of adamantane and tricyclo[4.3.1.1^{3,8}]undecane compounds having an aminomethyl or N-substituted aminomethyl group attached to a tertiary or bridgehead nuclear carbon atom which are useful antiviral agents. Typical compounds of this class are 1-(aminomethyl)adamantane, 3-(aminomethyl)tricyclo[4.3.1.1^{3,8}]undecane, α -methyl-1-adamantanemethylamine, and 1-(N-methylaminomethyl)adamantane and are acid addition compounds of the above described class of adamantane and tricyclo[4.3.1.1^{3,8}]undecane compounds.

Cross-reference

This application is a continuation-in-part of my pending application S.N. 297,233, filed July 24, 1963, now abandoned.

According to the present invention, I have discovered a class of novel compounds having pharmaceutical application and useful as antiviral agents. They have the ability to inhibit and deter incidence and growth of harmful viruses. Additionally, compounds of this class of compounds exhibit significant stimulant activity.

The compounds of this invention are adamantanes of the formula

(1)

and tricyclo[4.3.1.1^{3,8}]undecanes of the formula

(2)

2

where

X and Y can be the same or different and are hydrogen, methyl or ethyl; and

5 R is $-\text{N}(\text{CH}_2)_n-$

where n is 2, 3, 4, 5, or 6; $-\text{NR}_1\text{R}_2$; or $-\text{N}=\text{CHR}_3$

10 wherein R₁ is hydrogen; alkyl of 1 through 6 carbon atoms; mono-substituted alkyl of 1 through 6 carbon atoms where the substituent is hydroxy, alkoxy of 1 through 2 carbon atoms, $-\text{NH}_2$, $-\text{NHR}_4$, or $-\text{NR}_4\text{R}_5$ where R₄ and R₅ can be the same or different and each is an alkyl radical of 1 through 4 carbon atoms; alkenyl 15 of 2 through 6 carbon atoms; alkynyl of 2 through 6 carbon atoms; cyclopropyl; cyclobutyl; cyclopropylmethyl; cyclobutylmethyl;

20 R₂ is R₁; chlorine; bromine; formyl; $-\text{CH}_2\text{COOH}_3$; or $-\text{CH}_2\text{COOC}_2\text{H}_5$ with the proviso that when R₁ is alkenyl or alkynyl having the unsaturated bond in the 1-position, R₂ is alkyl or mono-substituted alkyl as above defined; and

25 R₃ is aliphatic; mono-substituted aliphatic where the substituent is aromatic or heterocyclic; aromatic; or heterocyclic containing not more than 12 carbon atoms.

Compounds hydrolyzable to the compounds of Formulas 1 and 2 are for most purposes equivalent to those compounds and are of course contemplated as within the present invention.

30 It also will be understood that the compounds within the scope of Formulas 1 and 2 having a basic amino group, readily form salts and such salts having a non-toxic anion are also included within the scope of the present invention. Representative of such salts are hydrochlorides,

35 hydrobromides, sulfates, phosphates, acetates, succinates, adipates, propionates, tartrates, citrates, bicarbonates, pamoates, cyclohexylsulfamates and acetylsalicylates. Of these the hydrochlorides, acetates and cyclohexylsulfamates are preferred. The cyclohexylsulfamates have a

40 pleasant taste and thus are particularly useful in preparing syrups for oral administration. Additionally the cyclohexylsulfamates have usefulness in making uncoated tablets for oral administration which have no objectionable bitter taste. Other salts include those with capro- 45 chlorone and with penicillin. In general, the salts described above enhance the usefulness of the relatively insoluble amines in pharmaceutical applications.

Within the overall scope of the compounds of the invention, various sub-classes of compounds are found to 50 provide particularly useful combinations of properties. For example, by proper selection of compounds, it is found that it is possible to attain different desired balances of stimulant and anti-viral activities as well as different desired balances of drug dynamics and anti-viral activities 55 depending upon the type of disease and patient being treated.

Accordingly, compounds of the invention are preferred where the amine on the adamantane or undecane moiety is substituted with dialkyl (N,N-dialkylated compounds)

60 because they provide a very favorable balance of anti-viral activity with reduced stimulant activity. Of these, the lower alkyl substituents such as the dimethyl and diethyl derivatives are most preferred from considerations of higher anti-viral activity. Compounds of the invention 65 where the amine on the adamantane or undecane moiety is monoalkylated also demonstrate reduced stimulant activity in comparison to the unsubstituted amine. These monoalkylated amine derivatives do not reduce stimulant activity to the degree of the dialkylated amine derivatives but the monoalkylated amine derivatives, particularly the monomethyl and monoethyl derivatives, exhibit higher anti-viral activity than the dialkylated amine derivatives.

Preferred compounds of the invention from the standpoint of a balance of anti-viral activity and favorable drug dynamics, chiefly longer acting prior to degradation or excretion, are those where the methylamino group on the adamantanone or undecane moiety is α -substituted or α,α -substituted. Generally within this class of compounds, the α -substituted compounds exhibit higher anti-viral activity but less favorable drug dynamics in comparison to the α,α -substituted compounds.

In view of the foregoing considerations, the most preferred compounds of the invention for pharmaceutical application are the following compounds and their hydrochloride salts:

- 1-(N,N-dimethylaminomethyl)adamantanone
- 1-(N-methylaminomethyl)adamantanone
- 1-(N-ethyl-N-methylaminomethyl)adamantanone
- 1-(aminomethyl)adamantanone
- 1-(N,N-diethylaminomethyl)adamantanone
- 1-(N-ethylaminomethyl)adamantanone
- 3-(N,N-dimethylaminomethyl)tricyclo[4.3.1.1^{3,8}]undecane
- 3-(N-methylaminomethyl)tricyclo[4.3.1.1^{3,8}]undecane
- 3-(N-ethyl-N-methylaminomethyl)tricyclo[4.3.1.1^{3,8}]undecane
- 3-(aminomethyl)tricyclo[4.3.1.1^{3,8}]undecane
- 3-(N,N-diethylaminomethyl)tricyclo[4.3.1.1^{3,8}]undecane
- 3-(N-ethylaminomethyl)tricyclo[4.3.1.1^{3,8}]undecane
- α -methyl-1-adamantanemethylamine
- α -methyl-3-tricyclo[4.3.1.1^{3,8}]undecanemethylamine
- α,α -dimethyl-1-adamantanemethylamine
- α,α -dimethyl-3-tricyclo[4.3.1.1^{3,8}]undecanemethylamine

The compounds of this invention can be prepared by a variety of methods.

1-adamantanone carboxylic acid and 3-tricyclo[4.3.1.1^{3,8}]undecane carboxylic acid can be converted to the corresponding acid chlorides with thionyl chloride. The unsubstituted amides and a variety of N-alkyl- and N,N-dialkyl-substituted amides can be prepared from the acid chlorides by reaction with the appropriately substituted amines and ammonia. These amides are then reduced with lithium aluminum hydride to the corresponding amino-, N-alkyl-amino- and N,N-dialkylaminomethyl-adamantanes and tricycloundecanes.

The α -alkyl-1-adamantanemethylamines and α -alkyl-3-tricyclo[4.3.1.1^{3,8}]undecanemethylamines are prepared by reduction of adamantan-1(1) alkyl ketone oximes and tricyclo[4.3.1.1^{3,8}]undecyl-3(3) alkyl ketone oximes with lithium aluminum hydride. The ketones from which these oximes are derived are conveniently made by the reaction of the appropriate dialkyl cadmium with 1-adamantoyl chloride or 3-tricyclo[4.3.1.1^{3,8}]undecoyl chloride.

The α,α -dialkyl-1-adamantanemethylamines and α,α -dialkyl-3-tricyclo[4.3.1.1^{3,8}]undecanemethylamines are made by the reaction of acetonitrile and sulfuric acid (Ritter reaction) with the corresponding α,α -dialkyl-1-adamantanemethanol or α,α -dialkyl-3-tricyclo[4.3.1.1^{3,8}]undecanemethanol, which gives the N-acetyl- α,α -dialkyl-1-adamantanemethylamine or N-acetyl- α,α -dialkyl-3-tricyclo[4.3.1.1^{3,8}]undecanemethylamine. The amine is obtained by alkaline hydrolysis. The starting alcohols for these reactions are made by the reaction of 1-adamantoyl chloride or 3-tricyclo[4.3.1.1^{3,8}]undecoyl chloride with alkyl Grignard reagents.

A variety of amines can be used for the preparation of 1-adamantanecarboxamides and 3-tricyclo[4.3.1.1^{3,8}]undecanecarboxamides, to give a variety of substituent groups on the nitrogen of 1-(aminomethyl)adamantanone and 3-(aminomethyl)tricyclo[4.3.1.1^{3,8}]undecane. For example, reactions of the acid chlorides with allylamine and diallylamine give the N-allyl and N,N-diallyl compounds after reduction. Reactions of the acid chlorides with propargylamine and dipropargylamine give the N-propargyl and N,N-dipropargyl compounds after reduction. Reactions with cyclopropylamine, cyclopropylmethylamine and

pyrrolidine give the N-cyclopropyl, N-cyclopropylmethyl and pyrrolidino compounds after reduction. Reactions with alkoxyalkylamines give the N-alkoxyalkyl compounds after reduction. Of course, reactions of the acid chlorides with amines having different N-substituents give corresponding N,N-disubstituted amino compounds. For instance, reactions of the acid chlorides with N-allyl-N-methylamine give 1-(N-allyl-N-methylaminomethyl)adamantanone and 3-(N-allyl-N-methylaminomethyl)tricyclo[4.3.1.1^{3,8}]undecane.

Some substituted alkyl amino compounds are more easily made by other routes. Hydroxyethyl- and bis-hydroxyethyl compounds are made by reaction of the amine with ethylene oxide. N-carbalkoxymethylamino compounds are made by alkylation with alkyl chloroacetate and base. Aminoalkyl-, alkylaminoalkyl-, and dialkylaminoalkyl compounds are made by alkylation with appropriate aminoalkyl halides and base, although they can be made by treating the corresponding hydroxyalkyl compound with a thionyl halide to replace the hydroxyl group with a halogen and then replacing the halogen with the amino, alkylamino, or dialkylamino group by reaction with ammonia or a primary or secondary amine.

In some cases, N-alkyl- and N,N-dialkyl-compounds are easily made by alkylation of 1-(aminomethyl)adamantanone and 3-(aminomethyl)tricyclo[4.3.1.1^{3,8}]undecane with alkylating agents (such as alkyl halides), without resorting to reduction of N-alkyl- and N,N-dialkyl-amides.

When the reagents are used in molar amounts, the monoalkylamino compound is generally formed as the major product, whereas greater amounts of the reagents give the dialkylamino compound. This method is not as clean-cut as reduction of the amides which is why it is less preferred. However, it sometimes becomes the method of choice because it involves fewer steps.

Ethylene chloro- and bromo-hydrin, and alkoxyalkyl halides can be used to alkylate the amino nitrogen, to give the hydroxyethyl- and alkoxyalkyl-substitutions. For the reasons just given, these reactions are less preferable than other methods but may be preferred in certain instances, and they illustrate an alternate route to substituted - alkylaminomethyltricyclo[4.3.1.1^{3,8}]undecanes and adamantanones by ordinary alkylation with a substituted alkylating reagent.

Reactions of 1-(aminomethyl)adamantanone and 3-(aminomethyl)tricyclo[4.3.1.1^{3,8}]undecane with aldehydes give the corresponding alkylidene, arylidene or heterocycliclylidene aminomethyladamantanones and aminomethyltricycloundecanes. For instance, reaction of 1-(aminomethyl)adamantanone with formaldehyde gives N-(1-adamantylmethyl)azomethine. Reaction of 3-(aminomethyl)tricyclo[4.3.1.1^{3,8}]undecane with benzaldehyde gives 3-(benzylideneaminomethyl)tricyclo[4.3.1.1^{3,8}]undecane.

Reactions of 1-(aminomethyl)adamantanone or 3-(aminomethyl)tricyclo[4.3.1.1^{3,8}]undecane or the corresponding 1-(N-alkylaminomethyl) compounds with butyl formate give the formamido-compounds.

Representative of the compounds of this invention are the following compounds and their salts:

- 1-(aminomethyl)adamantanone
- 1-(N-methylaminomethyl)adamantanone
- 1-(N,N-dimethylaminomethyl)adamantanone
- 1-(N-ethyl-N-methylaminomethyl)adamantanone
- 1-(N,N-diethylaminomethyl)adamantanone
- 1-(N-propylaminomethyl)adamantanone
- 1-(N-methyl-N-propylaminomethyl)adamantanone
- 1-(N-isopropylaminomethyl)adamantanone
- 1-(N-methyl-N-isopropylaminomethyl)adamantanone
- 1-(N,N-diisopropylaminomethyl)adamantanone
- 1-(N-sec-butylaminomethyl)adamantanone
- 1-(N-isobutylaminomethyl)adamantanone
- 1-(N-tert-butylaminomethyl)adamantanone
- 1-(N-hexylaminomethyl)adamantanone
- 1-(N-isoamylaminomethyl)adamantanone

 65 This invention will be more fully understood by reference to the following illustrative examples in which parts and percentages are by weight unless otherwise indicated.

Example 1

70 A solution of 6 parts of 1-adamantane carboxamide in 200 parts of tetrahydrofuran is added slowly to a well-stirred suspension of 6.15 parts of lithium aluminum hydride in 200 parts of dry diethyl ether. After completion of addition, the mixture is refluxed for one hour and

the solvent distilled off. The residue is subjected to steam distillation. The waxy 1-aminomethyl adamantane is extracted from the steam distillate with ether and the ethereal solution dried with solid potassium hydroxide. Dry hydrogen chloride is then passed into the ether solution to precipitate the amine hydrochloride. The yield is 5.25 parts of 1-(aminomethyl)adamantane hydrochloride which melts at 337-340° C. after recrystallization from chloroform-benzene.

Analysis.—Calcd. for $C_{11}H_{20}NCl$: C, 65.6; H, 9.93; N, 6.96. Found: C, 65.16; H, 10.06; N, 6.94.

The free 1-aminomethyl adamantane melts at 128.5° C. and can be converted to an acetyl derivative by treatment with acetic anhydride which, after recrystallization from n-hexane, melts at 123-124°.

Analysis.—Calcd. for $C_{13}H_{21}ON$: C, 75.31; H, 10.20; N, 6.76. Found: C, 75.45; H, 9.97; N, 7.08.

Example 2

A solution of 17 parts of 1-adamantoyl chloride in 150 parts of acetone is treated with 15 parts of a 40% aqueous solution of methylamine at 0° C. After complete addition, the mixture is warmed gently and diluted with water. The crystalline 1-N-methyl adamantane carboxamide is isolated by filtration as 11.27 parts of material melting at 137-138° C. In an alternative synthesis of this compound, dry methylamine, 2 equivalents, is distilled into an ethereal solution of adamantoyl chloride, 1 equivalent, and the resulting solution evaporated to dryness. The product is washed thoroughly with water to remove the methylammonium chloride formed and dried in vacuum to give a 96% yield of 1-N-methyl adamantane carboxamide. A solution of 11 parts of the crude amide in 100 parts of tetrahydrofuran is added slowly to a suspension of 2.4 parts of lithium aluminum hydride in 100 parts of ether. After complete addition, the mixture is refluxed for one hour, the solvent distilled off, and the residue subjected to steam distillation. The steam distillate is extracted with cyclohexane, the cyclohexane solution dried with solid sodium hydroxide and dry hydrogen chloride passed into the solution. The solid 1-(N-methylaminomethyl)adamantane hydrochloride is recrystallized from ethanol to give crystals melting at 324.5-325° C. in a sealed capillary.

Analysis.—Calcd. for $C_{12}H_{22}NCl$: N, 6.51. Found: N, 6.11.

Example 3

A solution of 19.85 parts of 1-adamantoyl chloride in 100 parts of dry diethyl ether is stirred at 0° C. and an ethereal solution of 9 parts of dimethylamine added slowly. The mixture is then stirred at room temperature for 30 minutes and evaporated to dryness. The residual solid is triturated with water and extracted with ether. The ethereal solution is dried over anhydrous sodium sulfate and the ether removed. This gives 19.5 parts (94.2%) of 1-N,N-dimethyl adamantane carboxamide which melts at 76-78° C. The 19.5 parts of amide is dissolved in 100 parts of ether and added slowly to a well stirred suspension of 4.5 parts of $LiAlH_4$ in 300 parts of ether. After complete addition the reaction is refluxed for 1 hour and the solvent removed. The residue is steam distilled to give 1-(N,N-dimethylaminomethyl)adamantane in the distillate. The steam distillate is extracted with cyclohexane, the extract dried with sodium hydroxide and dry hydrogen chloride passed into the solution. The yield of 1-(N,N-dimethylaminomethyl)adamantane hydrochloride is 17 parts or 84%. The crystals melt at 254° in a sealed capillary after crystallization from methanol-ethyl acetate.

Analysis.—Calcd. for $C_{14}H_{24}NCl$: C, 68.20; H, 10.51; N, 6.1. Found: C, 66.94; H, 10.57; N, 5.94.

Example 4

A solution of 19.85 parts of 1-adamantoyl chloride is treated with 9 parts of ethylamine under the condi-

tions outlined in the previous example to give 19.56 parts, 94.5%, of 1-N-ethyl adamantane carboxamide melting at 138° C.

A tetrahydrofuran solution of this amide is reduced with $LiAlH_4$, as described in the previous example. After removal of the organic solvent the residue is refluxed with water for 10 minutes to facilitate filtration and filtered. Both the filtrate and the solid are extracted thoroughly with ether. The combined extracts are dried with sodium hydroxide and hydrogen chloride passed into the solution. This gives 19.68 parts (86% overall yield) of 1-(N-ethylaminomethyl)adamantane hydrochloride. The melting point, after recrystallization from methanol is 356° C.

Analysis.—Calcd. for $C_{13}H_{24}NCl$: C, 68.2; H, 10.51; N, 6.1. Found: C, 67.83; H, 10.43; N, 5.97.

Example 5

A solution of 19.85 parts of 1-adamantoyl chloride in ether is reacted with an ethereal solution of 12 parts of propylamine by the procedure of Example 3 to give 21.38 parts of 1-(N-propyl)adamantane carboxamide melting at 140-141° C. Twenty-one parts of this amide is reduced with $LiAlH_4$ as shown in the previous example to give 19.4 parts of 1-(N-propylaminomethyl)adamantane hydrochloride. After recrystallization from methanol, this melts at 342° C.

Analysis.—Calcd. for $C_{14}H_{26}NCl$: C, 69.1; H, 10.78; N, 5.76. Found: C, 68.86; H, 10.93; N, 5.80.

Example 6

Under the conditions of the previous example, 19.85 parts of 1-adamantoyl chloride and 14.67 parts of diethylamine give 22.8 parts of 1-N,N-diethyladamantane carboxamide, M.P. 62-63° C.

This amide when reduced with $LiAlH_4$ gives 22.7 parts of 1-(N,N-diethylaminomethyl)adamantane hydrochloride. This, after recrystallization from ethyl acetate-methanol, melts at 240-241° C.

Example 7

A solution of 5.8 parts of 3-carboxytricyclo[4.3.1.1^{3,8}]undecane in 10 parts of thionyl chloride is refluxed until hydrogen chloride evolution ceases. The crude acid halide thus prepared is isolated by distilling off the excess thionyl chloride under reduced pressure, adding a small amount of benzene and removing this under reduced pressure. The acid chloride is then dissolved in 200 parts of ether and an excess of dry methylamine passed into the stirred solution at 0° C. The reaction is then stirred for 30 minutes and diluted with water. The layers are separated, the ether layer washed with water and dried over calcium chloride. Removal of the solvent gives 3.7 parts of white leaflets, melting at 133° C., of N-methyltricyclo[4.3.1.1^{3,8}]undecyl-3-carboxamide.

A solution of this amide in 150 parts of tetrahydrofuran is added to a suspension of 2 parts of $LiAlH_4$ in 100 parts of diethyl ether. After complete addition, the mixture is refluxed for one hour and the solvent removed by distillation. Water is added slowly to the dry residue and the mixture then refluxed for ten minutes and filtered. Both the cooled filtrate and the solid filter cake are extracted thoroughly with ether, the ethereal solution dried with sodium hydroxide and excess dry hydrogen chloride passed into the solution. The amine hydrochloride which precipitates is isolated by filtration and recrystallized from methanolethyl acetate. A yield of 2.1 parts of 3 - N - methylaminomethyl)tricyclo[4.3.1.1^{3,8}]undecane HCl melting at 338° C., is obtained.

Example 8

The amine hydrochloride of Example 2, 5.4 parts, is dissolved in 20 parts of pyridine and 5 parts of acetic anhydride is added. The mixture is warmed gently until a clear solution is obtained, then heated on a steam bath

11

for 30 minutes and diluted with cold water. The solid which forms is isolated by filtration and recrystallized from ethyl acetate at -80° C . Thus, 1-(N-acetyl-N-methylaminomethyl)adamantane, melting at 90° C . is obtained in 72% yield (4.0 parts). This is dissolved in ether and added to 1 part of lithium aluminum hydride suspended in ether. The mixture is refluxed for 1 hour, and the amine is isolated as in Example 4. The product is 2.78 parts of 1-(N-ethyl-N-methylaminomethyl)adamantane hydrochloride, M.P. 251-251.5° C.

Example 9

A sample of 3-carboxamidotricyclo[4.3.1.1^{3,8}]undecane is prepared by converting the 3-carboxytricyclo[4.3.1.1^{3,8}]undecane of Stetter, Ber., 92, 1629-1635 (1959), to the acid chloride by treatment with thionyl chloride followed by treatment of the crude acid chloride with ammonia. The amide melts at 180-181° C. after recrystallization from acetone. The amide, 9.75 parts, is added in tetrahydrofuran solution, to 3 parts of lithium aluminum hydride suspended in 100 parts of ether. The mixture is refluxed one hour and the resulting amine is isolated as in Example 4. The product is 6.5 parts of 3-(aminomethyl)tricyclo[4.3.1.1^{3,8}]undecane hydrochloride, M.P. 352-352.5° C.

Example 10

A solution of 19.85 grams (0.10 mole) of 1-adamantoyl chloride in 100 milliliters of dry diethyl ether is stirred at 0° C . and an ethereal solution of 12.7 grams (0.15 mole) of piperidine is added slowly. The mixture is stirred at room temperature for 30 minutes and evaporated to dryness. The residual solid is triturated with water and extracted with ether. The ethereal solution is dried over anhydrous sodium sulfate and the ether removed to leave 1-adamantoylpiperide. A solution of 0.10 mole of 1-adamantoylpiperide in 100 milliliters of ether and added slowly to a well-stirred suspension of 4.5 grams of lithium aluminum hydride in 300 milliliters of ether. After complete addition, the reaction is refluxed for 1 hour and the solvent removed. Then, the residue is refluxed with 250 milliliters of water for 10 minutes, cooled, filtered, and both the filtrate and the solids are extracted thoroughly with ether. The combined extracts are dried with potassium hydroxide, and then hydrogen chloride is passed into the solution. The precipitate is filtered and dried to give N-(1-adamantylmethyl)piperidine hydrochloride.

Example 11

A mixture of 3.6 g. of magnesium turnings, a small crystal of iodine, 11 ml. of anhydrous benzene and 1 ml. of absolute ethanol is heated until a reaction begins. Then heating is discontinued and a mixture of 24.0 g. of diethyl malonate, 7.0 g. of absolute ethanol and 30 ml. of benzene is added dropwise at a rate which causes the reaction mixture to reflux. After addition is completed, the mixture is heated at reflux until the magnesium has dissolved. The excess ethanol is removed by azeotropic distillation with some of the benzene. To the resultant solution of ethoxymagnesiumdiethylmalonate is added a solution of 19.8 g. of 1-adamantoyl chloride in 30 ml. of anhydrous benzene, dropwise, over a 50-minute period. The reaction mixture is refluxed for an additional hour, and then cooled in an ice bath. To the cold mixture is added 50 g. of ice followed by sufficient 10% sulfuric acid to cause two clear layers to appear. The layers are separated and the aqueous layer is extracted with two 25-ml. portions of benzene. The extracts are combined with the organic layer, washed with 30 ml. of water, and dried with anhydrous sodium sulfate. The benzene is removed by vacuum concentration at 40°. A solution of 64 ml. of glacial acetic acid, 39 ml. of water and 7 ml. of concentrated sulfuric acid is added to the residue (32 g.), and the mixture is heated at reflux for 7 hours. Then it is cooled and poured into

ml. of water. The solid which separates is filtered and dried, and then recrystallized from methanol-water mixture to give 13.4 g. of white, crystalline adamantly-(1) methyl ketone, M.P. 53.5-55° C.

A mixture of 14 g. of hydroxylamine hydrochloride, 65 ml. of anhydrous pyridine and 65 ml. of anhydrous ethanol is heated on a steam bath until a clear solution is obtained. To this is added 13.4 g. of adamantly-(1) methyl ketone, and the mixture is heated at reflux for 2 hours, then cooled. It is concentrated to dryness in a vacuum at 70°, and the residue is suspended in 150 ml. of water and stirred well. The solids are filtered and dried to yield 14.2 g. of adamantly-(1) methyl ketone oxime, a white, crystalline compound melting at 180.5-182° C. This can be recrystallized from a dioxane-water mixture without affecting the melting point.

An 8.3-g. amount of adamantly-(1)methyl ketone oxime is added to a mixture of 3.3 g. of lithium aluminum hydride in 150 ml. of anhydrous tetrahydrofuran, and the mixture is stirred and heated at reflux for 3 hours. It is cooled in an ice bath and the excess of lithium aluminum hydride is destroyed with a water-tetrahydrofuran mixture. Several ml. of 10% sodium hydroxide solution is added to aid in the coagulation of the solids, which are removed by filtration, washed with 50 ml. of chloroform, and discarded. The filtrate, which includes the tetrahydrofuran solution and the chloroform solution, is saturated with dry hydrogen chloride and then concentrated to dryness in a vacuum at 50° C. The residue is placed in a separatory funnel and shaken with a mixture of 100 ml. of 10% sodium hydroxide and 300 ml. of ether. The aqueous layer is discarded and the ether solution is dried over potassium hydroxide pellets. Dry hydrogen chloride is passed into the ether solution until precipitation is complete, and the resultant amine hydrochloride is filtered and dried. This crude salt is dissolved in water, treated with excess 50% sodium hydroxide solution, and the free amine is extracted with ether. The ether extract is dried over potassium hydroxide pellets, decanted, and hydrogen chloride is passed until precipitation is complete. The precipitate is filtered and dried to yield 5.6 g. of white, crystalline α -methyl-1-adamantanemethylamine hydrochloride, M.P. 373-375° C. (sealed tube).

Analysis.—Calcd. for $C_{12}H_{22}NCl$: C, 66.82; H, 10.20; N, 6.49. Found: C, 66.52; H, 10.13; N, 6.38.

Example 12

Substitution of 21.3 g. of 3-tricyclo[4.3.1.1^{3,8}]-undecyl chloride for the 19.8 g. of 1-adamantoyl chloride in Example 11 and repetition of the procedure of that example leads to tricyclo[4.3.1.1^{3,8}]-undecyl-(3) methyl ketone, then to tricyclo[4.3.1.1^{3,8}]-undecyl-(3) methyl ketone oxime, and, after the reduction, to α -methyl-1-tricyclo[4.3.1.1^{3,8}]-undecanemethylamine hydrochloride.

Example 13

To a solution of 31.5 g. of 1-adamantoyl chloride in 500 ml. of anhydrous ether under a nitrogen atmosphere is added, dropwise, 150 ml. of commercial 3 M methyl magnesium bromide at a rate which maintains a gentle reflux. The reaction mixture is heated for 1 hour after the addition, then cooled. To decompose the metal complex, 300 ml. of saturated ammonium chloride is added. The ether layer is separated and the aqueous layer is extracted with 100 ml. of chloroform. This extract is combined with the ether layer, and the mixture is dried with anhydrous magnesium sulfate and vacuum-concentrated to dryness at 35° C. The residue is steam-distilled until the distillate is no longer milky, about 3 liters of distillate being collected. On cooling, the steam distillate crystallizes. The solids are filtered and dried to yield 26.9 g. of α , α -dimethyl-1-adamantanemethanol, M.P. 77-78° C.

13

A 35-ml. amount of concentrated sulfuric acid is added dropwise with cooling to hold the temperature below 10° C. to 160 ml. of acetonitrile. Then, 21 g. of α,α -dimethyl-1-adamantanemethanol is added. The temperature is raised to 48° C. and maintained at 48° C. for 45 minutes. The reaction mixture is allowed to cool to room temperature and is then slowly poured into 1000 ml. of ice water. The solids which separate are filtered and dried to yield 24.2 g. of crude product. This is taken up in 500 ml. of ether and dry hydrogen chloride is bubbled into the ether solution until no further precipitation occurs. The solids are filtered, dried, and placed in a separatory funnel containing 200 ml. of water and 500 ml. of ether. This is shaken until the solids dissolve, and the aqueous layer is separated and discarded. The ether solution is dried with anhydrous sodium sulfate and concentrated to dryness to give white crystals of N-acetyl- α,α -dimethyl-1-adamantanemethylamine.

A mixture of 2.0 g. of N-acetyl- α,α -dimethyl-1-adamantanemethylamine, 10 g. of potassium hydroxide and 40 ml. of methanol is heated at 225° C. in a sealed tube for 18 hours, then cooled. The tube contents are added to 100 ml. of water, and the mixture is extracted with two 50-ml. portions of ether. The extracts are combined, dried with potassium hydroxide pellets, and dry hydrogen chloride is bubbled in until precipitation is complete. The precipitate is filtered and dried to give 1.8 g. of crude salt. This is dissolved in 80 ml. of water and treated with an excess of 50% sodium hydroxide. The amine precipitates, and is filtered and dried, M.P. 103–105° C. This is taken up in ether and precipitated with hydrogen chloride. The hydrochloride is filtered and dried. The melting point of α,α -dimethyl-1-adamantanemethylamine hydrochloride is 340–345° C. (sealed tube).

Analysis.—Calcd. for $C_{15}H_{24}NCl$: C, 67.98; H, 10.45; N, 6.10. Found: C, 67.75; H, 10.35; N, 6.17.

Example 14

Substitution of 33.7 g. of 3-tricyclo[4.3.1.1^{3,8}]undecoyl chloride for the 31.5 g. of 1-adamantoyl chloride in Example 13 and repetition of the procedure of that example leads to α,α -dimethyl-3-tricyclo[4.3.1.1^{3,8}]undecanemethanol, then to N-acetyl- α,α -dimethyl-3-tricyclo[4.3.1.1^{3,8}]undecanemethylamine, and, after hydrolysis, to α,α -dimethyl-3-tricyclo[4.3.1.1^{3,8}]undecane methylamine hydrochloride.

Example 15

To a mixture of 1.5 g. of lithium aluminum hydride in 100 ml. of anhydrous diethylene glycol, dimethyl ether is added 4.1 g. of N-acetyl- α,α -dimethyl-1-adamantanemethylamine, prepared in Example 13. The reaction mixture is stirred and heated at reflux for 3 hours, then cooled in an ice bath. The excess lithium aluminum hydride is decomposed by adding wet diethylene glycol, dimethyl ether. Several ml. of 10% sodium hydroxide is added to coagulate the precipitate, which is then filtered and washed with 50 ml. of ether. The filtrate is treated with dry hydrogen chloride until no additional precipitate forms. This is filtered, dissolved in 100 ml. of water, and an excess of 50% sodium hydroxide is added. The mixture is extracted with three 30-ml. portions of ether, and the ether extracts are combined, dried with potassium hydroxide pellets, and treated with hydrogen chloride until precipitation is complete. This precipitate is filtered and dried to yield 3.2 g. of N-ethyl- α,α -dimethyl-1-adamantanemethylamine hydrochloride, M.P. 276–279° C. (sealed tube).

Analysis.—Calcd. for $C_{15}H_{28}NCl$: C, 69.91; H, 10.87; N, 5.44. Found: C, 69.33; H, 11.00; N, 5.67.

Example 16

Substitution of 4.5 g. of N-acetyl- α,α -dimethyl-3-tricyclo[4.3.1.1^{3,8}]undecanemethylamine, prepared in Example 14, for the 4.1 g. of N-acetyl- α,α -dimethyl-1-adamantanemethylamine and repetition of the procedure

14

of Example 15, leads to N-ethyl- α,α -dimethyl-3-tricyclo[4.3.1.1^{3,8}]undecanemethylamine hydrochloride.

Example 17

A solution of diethyl cadmium in benzene is prepared by adding 19.6 g. of powdered anhydrous cadmium chloride over a 5-minute period to 0.2 mole of ethyl magnesium bromide in 100 ml. of anhydrous ether at ice bath temperature. The mixture is heated at reflux with vigorous stirring for 30 minutes. Then, the ether is removed by distillation on a steam bath, and 65 ml. of benzene is added to the nearly dry, brown, pasty residue. Distillation is continued until the vapor temperature of the distillate reaches 61° C. An additional 100 ml. of benzene is added to the diethyl cadmium solution, and the solution is again heated to reflux. Heating is discontinued, vigorous stirring is begun, and a solution of 19.8 g. of 1-adamantoyl chloride is added as rapidly as the exothermic reaction will allow. Refluxing and stirring is continued for an additional 45 minutes. The reaction mixture is cooled in an ice bath and 200 g. of water and ice is added, followed by 150 ml. of 20% sulfuric acid. The benzene layer is separated and the aqueous layer is extracted with 75 ml. of benzene. The benzene solutions are combined, dried with anhydrous sodium carbonate, and the benzene is removed by vacuum concentration at 50° to yield a liquid residue. This crystallizes on cooling, giving 21.6 g. of adamantlyl-(1) ethyl ketone, M.P. 30.5–32.5° C.

A mixture of 75 ml. of anhydrous ethanol, 75 ml. of anhydrous pyridine, 16 g. of hydroxylamine hydrochloride and 16.0 g. of adamantlyl-(1) ethyl ketone is heated at reflux for 2 hours and then vacuum concentrated to semi-dryness at 80° C. A 200-ml. amount of water is added, and the mixture is again concentrated to semi-dryness. The residue is suspended in 300 ml. of water, and the solids are filtered. The melting point of this crude material is 175–177° C. Recrystallization from a mixture of dioxane and acetonitrile gives 10.3 g. of white, crystalline adamantlyl-(1) ethyl ketone oxime, M.P. 177–179° C.

A 7.7-g. quantity of adamantlyl-(1) ethyl ketone oxime is added to a mixture of 3.0 g. of lithium aluminum hydride and 150 ml. of anhydrous diethylene glycol dimethyl ether, and the mixture is stirred and heated at reflux for three hours. It is cooled to 10° C. with an ice bath and the excess lithium aluminum hydride is destroyed with wet diethylene glycol dimethyl ether. Five ml. of 10% sodium hydroxide is added to coagulate the solids, which are then filtered, washed with 50 ml. of ether and discarded. The filtrate is saturated with dry hydrogen chloride and vacuum concentrated until precipitation is complete. The concentrated filtrate is cooled and the solids are filtered, washed with ether and dried. The dried salt is dissolved in 150 ml. of water and the solution is treated with excess 50% sodium hydroxide and extracted with two 50-ml. portions of ether. The ether extracts are combined, dried with potassium hydroxide pellets, and treated with dry hydrogen chloride until precipitation is complete. The precipitate is filtered and dried to give 5.2 g. of white, crystalline α -ethyl-1-adamantanemethylamine hydrochloride, M.P. 278–282° C. (sealed tube).

Analysis.—Calcd. for $C_{13}H_{24}NCl$: C, 67.99; H, 10.45; N, 6.10. Found: C, 68.55; H, 10.48; N, 6.14.

Example 18

Substitution of 21.3 g. of 3-tricyclo[4.3.1.1^{3,8}]undecoyl chloride for the 19.8 g. of 1-adamantoyl chloride in Example 17, and repetition of the procedure of that example leads to tricyclo[4.3.1.1^{3,8}]undecyl-(3) ethyl ketone, then to tricyclo[4.3.1.1^{3,8}]undecyl-(3) ethyl ketone oxime, and, after the reduction, to α -ethyl-3-tricyclo[4.3.1.1^{3,8}]undecanemethylamine hydrochloride.

Example 19

Use of 0.10 mole of 3-tricyclo[4.3.1.1^{3,8}]undecoylchlo-

15

ride (see Example 7) and 0.15 mole of N-(3-methoxypropyl)-methyl amine instead of the 1-adamantoyl chloride and piperidine in the procedure of Example 10 gives 3-[N-(3-methoxypropyl)-N-methylaminomethyl]tricyclo[4.3.1.1^{3,8}]undecane hydrochloride.

Example 20

Use of 0.15 mole of allylamine instead of the 0.15 mole of piperidine in Example 10 gives 1-(N-allylaminomethyl)adamantane hydrochloride.

Example 21

Use of 0.10 mole of 3-tricyclo[4.3.1.1^{3,8}]undecoylchloride (see Example 7) and 0.15 mole of diallylamine instead of the 1-adamantoyl chloride and piperidine in the procedure of Example 10 gives 3-(N,N-di-allylaminomethyl)tricyclo[4.3.1.1^{3,8}]undecane hydrochloride.

Example 22

Use of 0.15 mole of propargylamine instead of the 0.15 mole of piperidine in Example 10 gives 1-(N-propargylaminomethyl)adamantane hydrochloride.

Example 23

Use of 0.15 mole of cyclopropylmethylamine instead of the 0.15 mole of piperidine in Example 10 gives 1-(N-cyclopropylmethylaminomethyl)adamantane hydrochloride.

Example 24

Use of 0.10 mole of 3-tricyclo[4.3.1.1^{3,8}]undecoylchloride (see Example 7) and 0.15 mole of cyclobutylamine instead of the 1-adamantoyl chloride and piperidine in the procedure of Example 10 gives 3-(N-cyclobutylaminomethyl)-tricyclo[4.3.1.1^{3,8}]undecane hydrochloride.

Example 25

A 10 milliliter flask with magnetic stirrer and reflux condenser is charged with 0.050 mole of 1-(aminomethyl)adamantane, 6.13 grams (0.050 mole) of ethyl chloroacetate, 5.00 grams (0.060 mole) of sodium bicarbonate and 20 milliliters of methanol. The insoluble material is filtered and the filtrate is evaporated to dryness. The residue is dissolved in 60 milliliters of 1N hydrochloric acid, and 10 milliliters of 70% perchloric acid is added. The precipitated perchlorate salt is filtered, washed with cold water, and dried. The free base is regenerated with 10% sodium hydroxide and distilled to remove unchanged starting material. The higher boiling fraction is N-(1-adamantylmethyl)glycine, ethyl ester.

Example 26

A 100 milliliter flask with magnetic stirrer and reflux condenser is charged with 0.050 mole of 1-(N-methylaminomethyl)adamantane (see Example 2), 0.050 mole of freshly prepared 2-diethylaminoethyl chloride (from 2-diethylaminoethyl chloride, hydrochloride by neutralization and ether extraction), 5.0 grams (0.060 mole) of sodium bicarbonate and 20 milliliters of methanol. The mixture is refluxed overnight, then poured into 50 milliliters of cold water. The mixture is extracted with ether; the ether extract is dried with anhydrous magnesium sulfate, and concentrated in vacuo to give 1-[N-2-diethylaminoethyl]-N-methylaminomethyl]adamantane.

16

Example 27

A flask equipped with a Dean-Stark water separator is charged with 0.10 mole of 3-(aminomethyl)tricyclo[4.3.1.1^{3,8}]undecane (see Example 9), 15.4 grams (0.10 mole) of freshly distilled benzaldehyde, and 50 milliliters of toluene. The solution is allowed to reflux for 45 hours. The toluene is evaporated and the residue is recrystallized to give N-(3-tricyclo[4.3.1.1^{3,8}]undecylmethyl)benzaldimine.

Example 28

A solution of 0.5 mole of 1-(aminomethyl)adamantane in 120 milliliters of tetrahydrofuran and 30 milliliters of water is charged into a 400 milliliter stainless steel autoclave and 5.0 grams (0.11 mole) of ethylene oxide is injected. The autoclave is heated to 70° C. for 24 hours after which time it is cooled and cautiously vented. Solvent is removed at reduced pressure, and the residue is extracted with ether. The ether extract is dried with anhydrous potassium carbonate. Solvent is removed at reduced pressure and the residue is subjected to sublimation at 100° C./20 mm. in order to remove unreacted 1-(aminomethyl)adamantane. The residue from the sublimation is distilled under vacuum to yield 1-[N-(2-hydroxyethyl)aminomethyl]adamantane.

Example 29

A solution of 0.10 mole of 1-(aminomethyl)adamantane in 75 milliliters of 98% formic acid is allowed to stand 48 hours at room temperature. The formic acid is removed by concentration in vacuo to leave the residue, 1-(formamidomethyl)adamantane.

Alternatively, this compound is prepared by refluxing 0.05 mole of 1-(aminomethyl)adamantane for 19 hours in 25 ml. of butyl formate. The excess butyl formate is removed by vacuum concentration to leave a residue of 1-(formamidomethyl)adamantane.

Example 30

A suspension of 0.1 mole of 3-(aminomethyl)tricyclo[4.3.1.1^{3,8}]undecane in 100 milliliters of ice water is placed in a 500 milliliter flask equipped with mechanical stirrer and thermometer. The flask is cooled in an ice bath, and 142 grams of 5.25% sodium hypochlorite solution (commercial "Chlorox") is added at such a rate that the temperature does not exceed 10° C.

After the addition is complete the ice bath is removed and the mixture is stirred for 30 minutes. It is then extracted with three 50 milliliter portions of ether. The combined ether extracts are dried over calcium chloride. The solution is filtered and solvent is removed under vacuum to yield 3-(N-chloroaminomethyl)tricyclo[4.3.1.1^{3,8}]undecane.

Example 31

A mixture of 0.10 mole of 1-(aminomethyl)adamantane and 9.87 grams (0.10 mole) of 38% hydrochloric acid in 100 milliliters of water is concentrated in vacuo at 60° C. The resulting salt, 1-(aminomethyl)adamantane hydrochloride, is dried in vacuo at 60° C.

Examples 32 through 40

Example 18 is repeated, substituting the following indicated reactants for those of that example, to obtain the indicated product.

Example No.	Product of Example	Acid	Product
32	1 (free base).....	85% phosphoric acid (0.10 mole).....	1-(aminomethyl)adamantane, phosphate.
33	2 (free base) 0.10 mole).....	Sulfuric acid (0.050 mole).....	1-(N-methylaminomethyl)adamantane, sulfate.
34	3 (free base) (0.10 mole).....	Tartaric acid (0.10 mole).....	1-(N,N-dimethylaminomethyl)adamantane, bitartrate.
35	4 (free base) (0.10 mole).....	Tartaric acid (0.050 mole).....	1-(N-ethylaminomethyl)adamantane, ta trate.
36	5 (free base) (0.10 mole).....	Maleic acid (0.10 mole).....	1-(N-propylaminomethyl)adamantane, maleate.
37	6 (free base) (0.10 mole).....	Acetic acid (0.10 mole).....	1-(N,N-diethylaminomethyl)adamantane, acetate.
38	7 (0.10 mole).....	Succinic acid (0.050 mole).....	3-(N-methylaminomethyl)-tricyclo[4.3.1.1 ^{3,8}]undecane, succinate.
39	8 (0.10 mole).....	Mandelic acid (0.10 mole).....	1-(N-ethyl-N-methylaminomethyl)adamantane, mandelate.
40	9 (0.10 mole).....	Lactic acid (0.10 mole).....	3-(aminomethyl)tricyclo[4.3.1.1 ^{3,8}]undecane, lactate.

A solution of 0.20 mole of 1-(aminoethyl)adamantane hydrochloride in 100 milliliters of water is added to a solution of 0.10 mole of pamoic acid, disodium salt [4,4'-methylene - bis(3-hydroxy-2-naphthoic acid), disodium salt] in 500 milliliters of water. The resulting precipitate is filtered, washed well with water, and dried in vacuo to give 1-(aminomethyl)adamantane, pamoate.

Carbon dioxide is passed into a solution of 0.10 mole of 1-(aminomethyl)adamantane in 100 milliliters of ethyl ether until precipitation is complete. The precipitate is filtered and dried in vacuo to give 1-(aminoethyl)adamantane, bicarbonate.

The preceding examples can be repeated substituting equivalent amounts of appropriate starting materials to obtain other compounds of this invention including those listed hereinbefore.

The compounds of this invention can be administered in the antiviral treatment according to this invention by any means that effects contact of the active ingredient compound with the site of virus infection in the body. It will be understood that this includes the site prior to infection setting in as well as after. For example, administration can be parenterally, that is subcutaneously, intravaneously, intramuscularly, or intraperitoneally. Alternatively or concurrently, administration can be by the oral route.

The dosage administered will be dependent upon the virus being treated, the age, health and weight of the recipient, the extent of infection, kind of concurrent treatment if any, frequency of treatment, and the nature of the effect desired. Generally, a daily dosage of active ingredient compound will be from about 1 to 50 milligrams per kilogram of body weight, although lower, such as 0.5 milligram, per kilogram or higher amounts can be used. Ordinarily, from 1 to 20 and preferably 1 to 10 milligrams per kilogram per day, in one or more applications per day is effective to obtain the desired result.

The active ingredient of this invention can be employed in useful compositions according to the present invention in such dosage forms as tablets, capsules, powder packets, or liquid solutions, suspensions, or elixirs, for oral administration or liquid solutions for parenteral use, and in certain cases, suspensions for parenteral use (except intravenous). In such compositions the active ingredient will ordinarily always be present in an amount of at least 0.5% by weight based on the total weight of the composition and not more than 90% by weight.

Besides the active ingredient of this invention the anti-viral composition will contain a solid or liquid non-toxic pharmaceutical carrier for the active ingredient.

In one embodiment of a pharmaceutical composition of this invention, the solid carrier is a capsule which can be of the ordinary gelatin type. In the capsule will be from about 30-60% by weight of a compound of Formulas 1 and 2 and 70-40% of a carrier. In another embodiment, the active ingredient is tableted with or without adjuvants. In yet another embodiment, the active ingredient is put into powder packets and employed. These capsules, tablets and powders will generally constitute from about 5% to about 95% and preferably from 25% to 90% by weight. These dosage forms preferably contain from about 5 to about 500 milligrams of active ingredient, with from about 25 to about 250 most preferred.

The pharmaceutical carrier can, as previously indicated, be a sterile liquid such as water and oils, including those of petroleum, animal, vegetable or synthetic origin, for example peanut oil, soybean oil, mineral oil, sesame oil, and the like. In general, water, saline, aqueous dextrose (glucose) and related sugar solutions and glycols such as propylene glycol or polyethylene glycols are preferred liquid carriers, particularly for injectable solutions. Sterile

injectable solutions such as saline will ordinarily contain from about 0.5% to 25%, and preferably about 1 to 10% by weight of the active ingredient.

As mentioned above, oral administration can be in a suitable suspension or syrup, in which the active ingredient ordinarily will constitute from about 0.5 to 10%, and preferably about 2 to 5%, by weight. The pharmaceutical carrier in such composition can be a watery vehicle such as an aromatic water, a syrup or a pharmaceutical mucilage.

Suitable pharmaceutical carriers are described in "Remington's Practice of Pharmacy" by E. W. Martin and E. F. Cook, a well known reference text in this field.

In addition to the exemplary illustrations above, the following examples further explain the present invention:

A large number of unit capsules are prepared by filling standard two-piece hard gelatin capsules weighing about 20 50 milligrams each with 50 milligrams of powdered 1-(aminomethyl)adamantane, hydrochloride, 125 milligrams of lactose and 1 milligram of "Cab-o-sil."

Example 43 is repeated except that soft gelatin capsules are used and powdered 1-(aminomethyl)adamantane is first dissolved in mineral oil.

Example 43 is repeated except that the dosage unit is 50 milligrams of active ingredient, 5 milligrams of gelatin, 1.5 milligrams of magnesium stearate and 100 milligrams of lactose, mixed and formed into a tablet by a conventional tabletting machine. Slow release pills or tablets can also be used, by applying appropriate coatings. A sugar coating may be applied to increase palatability.

A parenteral composition suitable for administration by injection is prepared by stirring 5% by weight of the active ingredient of Example 43 in sterile aqueous 0.9% saline.

A large variety of compositions according to this invention can thus readily be made by substituting other compounds of this invention, and including specifically but not limited to compounds of this invention that have specifically been named hereinbefore. The compounds will be used in the amounts indicated in accordance with procedures well known and described in the Martin and Cook text mentioned above.

Compounds within the scope of Formulae 1 and 2 of the invention are anti-viral agents in domestic animals and livestock. As an illustration, compounds within the scope of Formulae 1 and 2 are effective against swine influenza and an embodiment of the invention, therefore, is a control of this infection by incorporating an active ingredient compound in the diet of the affected animal. For most purposes, an amount of active compound will be used to provide from about 0.0001% to 0.1% by weight of the active compounds based on the total weight of feed intake. Preferably, from 0.001% to 0.02% by weight will be used.

In like manner novel and useful compositions are provided by this invention which comprise at least one active ingredient compound within the scope of this invention in admixture with an animal feed. Descriptions of suitable feeds can be found in the book "Feeds and Feeding" by Frank B. Morrison, published by the Morrison Publishing Company of Ithaca, N.Y., 1948, 21st edition. The selection of the particular feed is within the knowledge of the art and will depend of course on the animal, the economics, natural materials available, the surrounding circumstances and the nature of the effect desired, as will be readily understood.

A particularly important composition according to this feature of the invention is a concentrate, suitable for preparation and sale to a farmer or livestock grower for addi-

tion to the animal's feedstuffs in appropriate proportion. These concentrates ordinarily comprise about 0.5% to about 95% by weight of the active ingredient compound together with a finely divided solid, preferably flours, such as wheat, corn, soya bean and cottonseed. Depending on the recipient animal, the solid adjuvant can be ground cereal, charcoal, fuller's earth, oyster shell and the like. Finely divided attapulgite and bentonite can be used, these latter materials also acting as solid dispersing agents.

The feed compositions, as well as the just-described concentrates, can additionally contain other components of feed concentrates or animal feeds, as will be readily understood. Other particularly important additives include proteins, carbohydrates, fats, vitamins, minerals, antibiotics, etc.

The disclosure herein should not be taken as a recommendation to use the disclosed invention in any way without full compliance with U.S. Food and Drug laws and other laws and governmental regulations which may be applicable.

The above and similar examples can be carried out in accordance with the teachings of this invention, as will be readily understood by persons skilled in the art, by substitution of components and amounts in place of those specified. Thus, the foregoing detailed description has been given for clearness of understanding only and no unnecessary limitations are to be understood therefrom.

The invention claimed is:

1. A compound selected from the group consisting of those of the formula

where

n is 0 or 1 with the proviso that when n is 0, A is

and B is hydrogen, and when n is 1,

B is

and A is hydrogen, and
wherein

5 X and Y are each hydrogen, methyl, or ethyl; and
R is

10 where n is an integer of from 2 through 6;

$-\text{NR}_1\text{R}_2$; or

$-\text{N}=\text{CHR}_3$

wherein

15 R_1 is hydrogen; alkyl of 1 through 6 carbon atoms; mono-substituted alkyl of 1 through 6 carbon atoms where the substituent is hydroxy, alkoxy of 1 through 2 carbon atoms, $-\text{NH}_2$, $-\text{NHR}_4$, or $-\text{NR}_4\text{R}_5$ where R_4 and R_5 are each alkyl of 1 through 4 carbon atoms; alkenyl of 2 through 6 carbon atoms; alkynyl of 2 through 6 carbon atoms; cyclopropyl; cyclobutyl; cyclopropylmethyl; or cyclobutylmethyl; R_2 is R_1 ; chlorine; bromine; formyl; $-\text{CH}_2\text{COOH}$; $-\text{CH}_2\text{COOCH}_3$; or $-\text{CH}_2\text{COOC}_2\text{H}_5$ with the proviso that when R_1 is alkenyl or alkynyl having the unsaturated bond in the 1-position, R_2 is alkyl of 1 through 6 carbon atoms or mono-substituted alkyl of 1 through 6 carbon atoms where the substituent is hydroxy, alkoxy of 1 through 2 carbon atoms, $-\text{NH}_2$, $-\text{NHR}_4$, and $-\text{NR}_4\text{R}_5$; and

R_3 is hydrogen, alkyl of 1 through 5 carbon atoms, phenyl, naphthyl or furyl; and non-toxic, acid-addition salts of the compounds of said formula.

20 2. 1-(N,N-dimethylaminomethyl)adamantane hydrochloride.

3. 1-(N-methylaminomethyl)adamantane hydrochloride.

4. 1-(aminomethyl)adamantane hydrochloride.

5. 3-(N-methylaminomethyl)tricyclo[4.3.1.1^{3,8}]undecane hydrochloride.

6. 3-(aminomethyl)tricyclo[4.3.1.1^{3,8}]undecane hydrochloride.

7. α -methyl-1-adamantanemethylamine hydrochloride.

8. α -methyl-3-tricyclo[4.3.1.1^{3,8}]undecanemethylamine hydrochloride.

9. α,α -dimethyl-1-adamantanemethylamine hydrochloride.

10. α,α -dimethyl-3-tricyclo[4.3.1.1^{3,8}]undecanemethylamine hydrochloride.
